EDWARD W. BRACKENBURY, OF MILWAUKEE, WISCONSIN, ASSIGNOR TO T. L. SMITH COMPANY, OF MILWAUKEE, WISCONSIN.

CONCRETE-MIXER.

1,052,035.

Specification of Letters Patent. Patented Feb. 4, 1913.

Application filed November 15, 1911. Serial No. 660,387.

To all whom it may concern:

Be it known that I, EDWARD W. BRACKENBURY, a citizen of the Kingdom of England, residing at Milwaukee, State of Wisconsin, have invented a new and useful Improvement in Concrete-Mixers, of which the following is a full and clear description, reference being had to the accompanying drawing, forming a part hereof.

0 My invention relates to improvements in concrete mixers, and it consists of the novel construction, combination and arrangement of parts hereinafter shown, described and claimed.

5 In the drawing—Figure 1 shows a mixer drum in elevation, a part being broken away to show a vertical section through some of the blades or buckets. Fig. 2 shows in plan view a section through the drum 0 taken on the broken line *a. b. c. d.* of Fig. 1, looking in the direction of the arrows. Fig. 3 shows a section through one of the buckets and portions of the head of the drum, taken on the line *e. f.* of Fig. 1 and 5 looking in the direction of the arrow.

Referring to the drawing by reference numerals, 1 is the cylindrical shell of the mixer drum, and 2. 2. are the heads thereof.

3 is the feed opening and 4 the discharge opening in the drum.

In the interior of the drum a plurality of blades or buckets is provided, each bucket consisting of a blade 5 placed substantially radial of the drum, a long inclined side 6, and a shorter inclined side 7. Both sides 6 and 7 and the blade 5 are formed integral preferably, consisting of one sheet of metal cut and bent to the requisite form. The extreme edges of the sides are flanged as at 8 and 9 and the bucket is secured in place in the drum by riveting these flanges to the heads 2. The ends of the inclined sides 6 and 7 are so cut that an opening 10 is left between them.

By considering the right hand half of Fig. 2 and corresponding part of Fig. 1 below the line *c. d.*, it will be seen that the radial blade 5, the shell of the drum, a portion of each head 2, and the inclined sides 6 and 7 altogether form a bucket with a wide open top which is in advance as the drum is rotated in the direction of the arrow 11, and the opening 10 on the side of this bucket toward the center of the drum, with the sides 6 and 7 converging to this

opening form a discharge chute for said bucket. This bucket discharge is nearer to the discharge opening 4 of the drum than it is to the feed opening 3 in order to facilitate the discharge from the drum, which 60 drum discharge is effected in the ordinary way by inserting an inclined spout in the opening 4 as is common in non-tilting batch mixers.

In operation the material in the drum is 65 lifted by the buckets and when the full batch is in the drum, the material immediately begins to flow through the constricted opening 10, and continues to flow through this opening by gravity until the 70 bucket has passed over the axis. During this action the material is moved from both ends of the drum toward the plane passing through the middle of the chutes 10. The material is continually turned over by the 75 lifting and pouring action of the buckets, and continually carried from the ends toward the middle of the drum by the inclined sides of the buckets 6 and 7.

What I claim as my invention is—

1. A rotatable mixing drum containing a plurality of tapering scoops, each scoop consisting of a bottom plate and two side plates substantially at right angles to the bottom plate and having its wider end attached to, and opening toward the periphery of, the drum, and its narrow end opening toward the axis of the drum. 80

2. A rotatable mixing drum containing a plurality of tapering, substantially radial 90 scoops, each scoop having its wider end extending the length of, and opening toward the periphery of the drum; and its narrow end opening toward the axis of the drum.

3. A rotatable mixing receptacle having 95 heads in its opposite ends and a shell connecting said heads, and a plurality of scoops in said receptacle, the opposite sides of each scoop being attached to the opposite heads and converging from said attachment toward the open end of the scoop which is toward the axis of the receptacle, the bottom of each scoop connecting the sides thereof and extending from the shell of the receptacle toward its axis. 100

4. A cylindrical mixing receptacle rotatably mounted having concentric feed and discharge openings in the opposite heads thereof, and a plurality of scoop-like partitions in said receptacle, each partition con- 110

sisting of two inclined sides respectively attached to the opposite heads of the drum and converging toward the axis of the drum, and a plate connecting the edges of 5 said sides which follow in the direction of rotation said plate extending substantially radial of the drum from the cylindrical shell thereof, the opening between the converging sides being directed toward the

axis of the drum, and nearer to the discharge end thereof than the feed end.

In testimony of which, I hereunto affix my hand in the presence of two witnesses.

EDWARD W. BRACKENBURY.
